[57] CLAIM

The ornamental design for a front panel unit for a bus, substantially as shown.

DESCRIPTION

FIG. 1 is a front elevational view of the front panel unit for a bus showing our new design;

FIG. 2 is a right side elevational view thereof;

FIG. 3 is a left side elevational view thereof;

FIG. 4 is a top plan view thereof.

FIG. 5 is an enlarged cross-sectional view thereof taken along line 5—5 in FIG. 1.

FIG. 6 is an enlarged cross-sectional view thereof taken along line 6—6 in FIG. 1; and

FIG. 7 is an enlarged cross-sectional view thereof taken along line 7—7 in FIG. 1.
